UNITED STATES PATENT OFFICE.

EDWARD P. SMITH, OF PITTSTON, PENNSYLVANIA.

DESIGN FOR AN EMBLEM, BUTTON, OR ARTICLE OF SIMILAR NATURE.

53,616.

Specification for Design.

Patented July 15, 1919.

Application filed September 9, 1918. Serial No 253,336. Term of patent 3½ years.

To all whom it may concern:

Be it known that I, EDWARD P. SMITH, a citizen of the United States, residing at Pittston, in the county of Luzerne and State of Pennsylvania, have invented a new, original, and ornamental Design for an Emblem, Button, or Article of Similar Nature, of which the following is a specification, reference being had to the accompanying drawing, forming part thereof.

The figure is a face view of a button, showing my new design.

I claim:—

The ornamental design for an emblem, button, or article of similar nature, as shown.

EDWARD P. SMITH.
